ABSTRACT

The disclosure herein describes an attachment to be added to a machine which normally forms open-side envelopes and thereby converts it to one capable of forming open-end envelopes. The attachment consists of a gum applying assembly adapted to be removably supported on a frame which is secured over the machine just prior to the scoring section thereof; this gum applying assembly consists of a series of rollers cooperating to transfer gum, collected from a gum recipient, to the scoring roller of the machine where it is applied on an envelope blank being conveyed below the scoring roller. The envelope blank is subsequently folded in the folding section of the machine in the usual manner to form an open-end envelope.

ENVELOPE FOLDING MACHINE

This invention relates to an attachment for use on an envelope folding machine; more particularly, this invention relates to an attachment for mounting on an envelope folding machine in order to convert this machine from one forming open-sided envelopes to one forming open-end envelopes.

Presently, in a plant for making envelopes, there are machines for making, for example, rectangularly shaped envelopes which have one open flap with a dried sealant set along one longitudinal side thereof and there are other machines for making similarly shaped envelopes which have one open flap with a dried sealant set along one lateral side thereof. Either one of these machines is very expensive since each machine must perform a series of successive operations, such as printing, gumming, scoring and folding; in some cases, an aperture is perforated through the envelope blank and a plastic window is glued over the aperture. However, no single machine exists which will perform all of the above operations and make an open-sided envelope as well as an open-end envelope.

It is an object of this invention to provide on a machine for normally forming open-sided envelopes an attachment which enables the same machine to form open-end envelopes.

A further important object of this invention is to provide on a machine which normally forms open-sided envelopes a removably mounted attachment which may be pivotally set in one position whereby the machine will form open-end envelopes and which may be retracted in an inoperating position so that the machine may revert to its original function, that is to form open-sided envelopes.

It is therefore another object of this invention to provide an attachment on a machine of the type described which is simple and efficient and which is of great economy and easy to operate.

The present invention relates to an attachment for mounting on a machine of the type described which comprises, in its broadest aspect, a supporting frame extending over an envelope conveying section of the machine; gum application means removably mounted relative to the scoring section of the machine; these means include a gum recipient, a first roller partially submerged in the gum recipient, a second roller adjacent the first roller and intermeshed therewith, a third roller adjacent the second roller and operatively connected therewith to rotate in the same rotational direction; the third roller is placed in juxtaposition with the scoring roller of the machine so that gum collected from the gum recipient is transferred via the first, second and third rollers to the scoring roller along the side edge of the envelope blank during the scoring operation thereof.

In a preferred embodiment of the invention, a rubber band is circumferentially disposed on the scoring roller of the machine; there, it receives the gum applied from the third roller and is rotated with the scoring roller to apply the gum to the envelope blank conveyed underneath the scoring roller.

The following is a description by way of example of one embodiment of the present invention, reference being had to the accompanying drawings in which:

FIG. 1 is a schematic side elevational view of a machine for forming open-side envelopes equipped with the attachment of the present invention in a non-operating position;

FIGS. 2 to 9 depict the series of transformations brought to an open-side envelope when formed by the machine shown in FIG. 1;

FIGS. 10 to 15 depict the series of transformations brought to an open-end envelope when formed by the machine shown in FIG. 1, but with the attachment lowered in an operating position;

FIG. 16 is a side elevational view of the attachment in operating position (full lines) and in non-operating position (phantom lines);

FIG. 17 is a front elevation view of the lever assembly in a raised position as seen along lines 17-17 of FIG. 16;

FIG. 18 is a partial front elevational view similar to that of FIG. 17 with the handle in a lowered position;

FIG. 19 is a partial top plan view of the attachment;

FIG. 20 is a side cross-sectional view taken along lines 20-20 of FIG. 19; and

FIG. 21 is a front elevational view of the two scoring rollers of the machine.

Referring to FIG. 1, there is shown a machine for forming open-side envelopes, one form of which is shown in FIGS. 2 to 9: an example of such a machine is one known in the envelope art as THE WINKLER & DÜNEBIER 127 GS MARK IV ENVELOPE MACHINE. All of the different sections of this machine illustrated in FIG. 1 are not essential to the understanding of the operation of the attachment in accordance with the present invention; hence, only a brief description of the different steps through which an envelope blank is processed will be given. A plurality of envelope blanks 30 are stacked at the feeding section A (see FIG. 2) from where each blank is successively processed to a printing section B, a window cutting section C (see FIG. 3), a window patching section D (See FIGS. 4 and 5), a seal flap gumming section (see FIG. 6), a drying section F, an aligner and conveying section G, a scoring section H, a gumming and folding section J (see FIGS. 7 and 8), and a delivery section K (see FIG. 9).

Referring to FIG. 1, the present invention relates to an attachment 32 which is adapted to be pivotally mounted on the machine between the aligner and conveying section G and the scoring section H and which, when lowered into an operating position, enables the same machine to form an envelope having an open end such as the one exemplified in FIGS. 10 to 15; these figures illustrate an envelope 34 at different stages of being formed into an open-end envelope (the reference letters accompanying the reference numerals 30 and 34 in FIGS. 2-15 designate the corresponding stage in the process of forming an envelope by the machine of FIG. 1). The function of attachment 32 is to lay a strip of gum 36 along one longitudinal side 38 of the envelope blank, as shown in FIG. 12. This strip of gum 36 is laid while the envelope is being scored and will permit side 38 to stick on side 40 after the envelope blank will have processed through the folding section.

Referring to FIGS. 16 and 19 more particularly, the attachment 32 consists of an inverted U-shaped frame 42 having an horizontal cross-member 44 with its op-

posite ends fixed to two vertical uprights 46 and 48 bolted respectively at 50 and 52 to the side frames 54 and 56 of the machine. The frame 42 supports a gum applicator assembly 58 which consists mainly of a gum recipient 60, a first roller 62 having its lower portion submerged in the gum recipient, a second roller 64 juxtaposed to roller 62 and a third roller 66 juxtaposed to roller 64. The gum applicator assembly 58 is pivotable on the supporting frame 42 through means of a lever assembly 68 with consists of a pair of lever arms 76 and 78 having their respective fulcrum points 80 and 82 (see FIG. 17) rotatably mounted in cross-member 44 of the supporting frame 52. Each lever arm 76, 78 has a motion transmitting end portion 69, 70 connected by means of pins 71, 72 to a pair of blocks 73, 74 disposed on each side of the gum recipient 60 and interconnected by means of a back plate 75 parallel to and spaced from member 44. These blocks are integral portions of two side arms 77, 79 extending along each side of the gum recipient 60 and providing support for the opposite upper side edges 61 and 63 of the gum recipient. Pivotal movement of lever arm 78 is effected by a cross-arm 84 having its opposite ends pivotally connected to arms 76 and 78. A handle extension 86 on lever arm 76 enables the pivotal movement of the lever assembly about fulcrum points 80 and 82 and, consequently, the whole gum applicator assembly 58 may be rotated down into a lowered position, as illustrated in FIG. 18.

Rollers 62, 64 and 66 are mounted on their respective rotating shafts 88, 90 and 92 which have their opposite ends rotatably mounted in the side arms 77 and 79. Intermeshing gears 98 and 99 are respectively fixed on shafts 88 and 90 while sprockets 100 and 102, operatively connected by chain 103, are respectively mounted on shafts 90 and 92. Shaft 88 further carries a second gear 104 which is meshed with gear 105 on a shaft 106 supported on the side frame 54 by suitable means 107 and rotated by means of a chain and sprocket arrangement 108 driven by a suitable power source (not shown) which may be the same power used for normally operating the machine.

Referring to FIG. 20, the gum collected by roller 62 in the gum bath of the recipient 60 is carried by rollers 64 and 66 and deposited on the scoring roller 110 of the machine so that it may be applied on the envelope blank 34 passing therebeneath. However, in order that the gum collected on the scorer 110 be properly transmitted and applied to the envelope, a rubber band 114 is, preferably, fixed circumferentially on the scorer to receive the gum from roller 66. It is evident that the positioning of the rubber band on the scorer 110 will be determined by the size of the envelope to be gummed; therefore, roller 66 is made longitudinally slideable on its shaft 92 to always be in alignment with the rubber band. Referring to FIGS. 20 and 21, a second roller 116 is provided on such a machine as referred to above and is disposed underneath the scorer 110 to complete the scoring operation and to assist in the conveying of the envelope 34 to the following gumming and folding section. However, a circumferential recess 118 is now required on roller 116 in order that the gum which is on the rubber band 114 remains on the rubber band and not transmitted on roller 116 when there is no envelope passing between the rollers 110 and 116. Roller 116 is

also made longitudinally slideable on shaft 120 so that recess 118 is always in alignment with the rubber band.

Referring to FIG. 20, it is essential that gum be properly transferred from the recipient 60 to the scorer 110. Therefore, with roller 62 rotating in a counter-clockwise fashion roller 64 turns clockwise due to the intermeshing of gears 98 and 99; a small gum deposit is usually collected between rollers 62 and 64; a scraper 122 fixed to side arms 77 and 79 removes any excess of gum on roller 62. A small spacing between rollers 64 and 66 enables an adequate transmission of gum between these two rollers; this spacing, however may be adjusted by means which are well-known in the art such as, for instance, screw 126 to adjust shaft 92. Similar adjusting screws 123, 125, 127 are provided on the gum application assembly to adjust the relative position of rollers 62, 64 and 66. It is further essential that the rotational direction of roller 66 be identical to that of roller 64; consequently, the chain 103 synchronizes the rotation of shafts 90 and 92. Otherwise, e.g., if shafts 90 and 92 were to be rotated in opposite directions, a roller 66 with a considerably large diameter would be required whereby the gum would dry on roller 66 before reaching the scoring roller 110 and gum splashing would occur if the diameter of roller 66 remain unaltered.

When the attachment is set in its inoperating position, it is set as illustrated in full lines in FIG. 16; thus, 30 the machine performs its usual function (that is, forming open-side envelopes) since roller 66 is separated from scorer 110 and gear 104 is separated from gear 105. When the attachment is set in its operating position, it is set as illustrated in phantom lines in FIG. 16. The lowering of the attachment 32 is effected by the operator pivoting handle 86 (see FIG. 17) about point 80. The whole lever assembly is thus pivoted about pins 80 and 82 transmitting a similar displacement to the 35 gum application assembly 58. When the gum application assembly arrives in its lowermost position, meshing engagement is effected between gear 104 and gear 105. At the same time, roller 66 is brought adjacent the rubber band 114 on the scorer 110; the transmittal of 40 rotation to roller 66 is effected from the power source via gear 104, gear 98, gear 99, sprocket 100, chain 103 and sprocket 102. With the gum application assembly 45 in operation, gum is transferred from the recipient onto the scoring roller 110 via roller 62, roller 64, roller 66 and rubber band 114.

Referring to FIGS. 12-15, while the strip of gum 36 is being applied along the edge 38 of the envelope blank 34, the latter is simultaneously scored by the scoring roller as indicated by dotted lines 35. It will be 50 evident that the folding section of the machine may be provided with a different size of folding blades to suit the particular shape and fold of an envelope blank.

While the invention has been discussed above only in relation to one specific form of the invention, persons skilled in the art will be aware that it may be refined and modified in various ways without departing from its scope. For instance, instead of being circumferential, the rubber band could be of shorter length and fixed on the scorer 110 so that its passage on the conveying table of the machine is made coincident with the passage of an envelope passing thereby, in such a case, the recess 118 on roller 116 would not be required. It is

therefore wished to have it understood that the present invention is not limited in interpretation except by the terms of the following claims.

What is claimed is:

1. In an envelope folding machine where an envelope blank is processed through a series of successive operations including gumming one edge transversely relative to the direction of travel of said blank in said machine, drying said gum to form a dried-gum flap, scoring said blank by means of a scoring roller and folding said blank to form an open-side envelope with a dried-gum flap, an attachment mounted on the machine forward of the scoring section thereof for additionally applying gum along one side edge of the envelope blank to form an open-end envelope comprising, in combination, a supporting frame extending over an envelope conveying section of the machine disposed adjacent the scoring section; gum application means supported by said frame and being removable relative to the scoring section, said means including a gum recipient, a first roller partially submerged in said gum recipient, a second roller adjacent said first roller, said first and second rollers respectively affixed on parallel rotatable shafts having intermeshing gears journaled thereon; a third roller adjacent said second roller and affixed on a rotatable shaft parallel to said shaft of said second roller and cooperating therewith by means of a chain and sprocket arrangement to thereby rotate in the same rotational direction; said third roller being juxtaposed to the scoring roller of the scoring section of the machine whereby gum collected in the recipient is transferred via the first and second rollers to the scoring roller and by the third roller to a rubber band circumferentially affixed to said scoring roller where it is applied along the side edge of the envelope blank being conveyed below said scoring roller during the scoring operation thereof, said side edge being subsequently folded in said folding section to form an open-end envelope with a dried-gum flap; said attachment further including a lever assembly having its fulcrum point pivotally secured to said supporting frame, said lever assembly consisting of members having one end secured to said gum application means and having a handle portion at the other end thereof whereby said gum application means are manually pivotable so that said third roller is removable relative to the scoring

roller.

2. In an envelope folding machine where an envelope blank is processed through a series of successive operations including gumming one edge transversely relative to the direction of travel of said blank in said machine, drying said gum to form a dried-gum flap, scoring said blank by means of a scoring roller and folding said blank to form an open-side envelope with a dried-gum flap, an attachment mounted on the machine forward of the scoring section thereof for additionally applying gum along one side edge of the envelope blank to form an open-end envelope comprising, in combination, a supporting frame extending over an envelope conveying section of the machine disposed adjacent the scoring section; gum application means supported by said frame and being removable relative to the scoring section, said means including a gum recipient, a first roller partially submerged in said gum recipient, a second roller adjacent said first roller, said first and second rollers respectively affixed on parallel rotatable shafts having intermeshing gears journaled thereon; a third roller adjacent said second roller and affixed on a rotatable shaft parallel to said shaft of said second roller and cooperating therewith by means of a chain and sprocket arrangement to thereby rotate in the same rotational direction; said third roller being juxtaposed to the scoring roller of the scoring section of the machine whereby gum collected in the recipient is transferred via the first and second rollers to the scoring roller and by the third roller to a rubber band circumferentially affixed to said scoring roller where it is applied along the side edge of the envelope blank being conveyed below said scoring roller during the scoring operation thereof, said side edge being subsequently folded in said folding section to form an open-end envelope with a dried-gum flap; said machine including a second scoring roller disposed below said scoring roller and wherein said second scoring roller is provided with a circumferential recess in alignment with said rubber band.

3. In an envelope folding machine as defined in claim 1 wherein said third roller is axially slidably on its shaft to thereby take various positions thereon in accordance with the dimensions of the envelope blank being conveyed below the scoring roller.
